UNITED STATES PATENT OFFICE

2,615,406

TRAVELING GRATE STOKER

Donald J. Mossart, Ardmore, Pa., assignor to
Westinghouse Electric Corporation, East Pittsburgh, Pa., a corporation of Pennsylvania

Application November 12, 1949, Serial No. 126,785

1 Claim. (Cl. 110—40)

1

This invention relates to stokers, more particularly to those of the traveling grate type, and has for an object to provide improved apparatus of this character.

Another object of the invention is to provide an improved scraper for removing ash from the discharge end of a traveling grate and directing it to an ash pit.

Yet another object of the invention is to provide a traveling grate stoker having a plenum chamber beneath the entire grate, together with an ash pit external to the plenum chamber.

A further object of the invention is to provide a reciprocating scraper for removing ash and refuse from the discharge end of the traveling grate of a stoker, said scraper being so arranged that it effectively encloses the ash discharge end of the grate and prevents flow of air from the plenum chamber to the ash pit.

These and other objects are effected by my invention as will be apparent from the following description and claim taken in connection with the accompanying drawings, forming a part of this application, in which:

Fig. 1 is a longitudinal sectional view through a traveling grate stoker constructed in accordance with the present invention;

Fig. 2 is a perspective view of the scraper; and

Fig. 3 is an enlarged fragmentary sectional view, taken along the line V—V of Fig. 4, looking in the direction indicated by the arrows.

Referring now to the drawings in greater detail, particularly to Fig. 1 thereof, the reference character 10 indicates, in its entirety, a traveling grate to which fuel is fed by mechanism of the spreader type, indicated in its entirety by the reference character 11. The fuel feeding mechanism 11 comprises a hopper 12 from which fuel discharges by gravity to a ram box 13 in which reciprocate one or more rams 14 which push fuel rearwardly (from left to right as viewed in Fig. 1) over a spill plate 16 from gravitational discharge over the rear edge 17 thereof to a rotary impeller 18 disposed therebelow. The blades 19 of the impeller project the fuel rearwardly through the fuel feed opening 21 in the front wall 22 of the furnace 23, and through the atmosphere of the combustion chamber 24 thereof above the fuel-supporting surface 26 of the traveling grate 10, the fine fuel particles burning in suspension and the heavier particles and pieces falling onto the rear portion of the grate whereon they are gradually advanced by forward travel of the upper run 27 of the grate 10 for discharge as ash and refuse to the ash pit 28.

2

The traveling grate 10 comprises the usual structural framework, including longitudinally-extending members 33 and transverse members 34 and 36 (Fig. 1). A pair of transverse spaced parallel shafts 37 and 38 are journaled in bearings (not shown) mounted in the members 33 and carry sprockets 39 on which are mounted the grate chains 41.

Each pair of chains 41 carries a plurality of grate bars 42 attached thereto by links 43 permitting limited pivotal movement of the bars between the two positions shown in Fig. 1 at the top run 27 and the bottom run 44. Each chain 41 is supported between its sprockets 39 by a series of rollers 46 mounted between adjacent pairs of structural members 33. Mechanism (not shown) functions to drive the left-hand sprocket counterclockwise as viewed in Fig. 1 for motivating the grate to effect travel of the upper run 27 from right to left.

A plenum chamber 50 is provided beneath the traveling grate and is defined by front and rear end walls 51 and 52, respectively, and side walls 53. A sealing structure 54—56 extends forwardly from the upper edge of the plenum chamber rear wall 52 in overlying relation to the rear sprocket 39 and the grate thereon.

At the front or discharge end of the grate there is a sealing and scraping member 57, hereinafter referred to as a scraper. The scraper includes a horizontal ash and refuse-receiving portion 58 adapted to rest upon the upper surfaces of the grate bars 42, and an ash and refuse-discharging portion 59 curved or inclined downwardly and away from the receiving portion 58, the two portions preferably being integral (Figs. 1 and 2).

As best shown in Fig. 2, the scraper 57 has a plurality of pairs of lugs 61, to which links 62 are connected by suitable means, such as the pins 63. The opposite ends of the links 62 are pivotally connected, by pins 64, to bifurcated arms 66 fixedly secured to a transversely-extending rocker shaft 67. It will be apparent from consideration of Fig. 1, that oscillation of the rocker shaft 67 will effect reciprocation of the scraper 57 in directions substantially parallel to the direction of travel of the grate upper run 27, and that during its rearward travel it will move beneath the discharging ash and refuse at the forward or left-hand end of the grate, as viewed in Fig. 1. To aid penetration of the receiving portion 58 of the scraper beneath the oppositely-moving bed of ash and refuse, the rearward edge

of the scraper is tapered or chamfered, as at 68 (Fig. 1).

The discharging portion 59 of the scraper overlies a horizontal surface 69 at the upper edge of the plenum chamber end wall 51 and is maintained in sealing relation thereto by one or more plates 71 movable vertically in slots 72 provided in the seal assembly 73 secured to the lower end of the scraper discharge portion 59 (Fig. 3). Thus, in effect, the scraper 57 functions as a continuation of the plenum chamber end wall 51, to limit upward discharge of air from the plenum chamber to that portion of the grate which supports the burning fuel bed.

While I have shown my invention in but one form, it will be obvious to those skilled in the art that it is not so limited, but is susceptible of various changes and modifications without departing from the spirit thereof.

What I claim is:

In a stoker, a traveling grate comprising a pair of transverse spaced parallel shafts, sprockets on said shafts, endless chains on said sprockets, transversely-extending grate bars secured to said chains with the upper run thereof providing a fuel-supporting grate surface, and structural members supporting the upper run of said grate bars for maintaining said fuel-supporting surface flat; wall structure defining a plenum chamber beneath the entire traveling grate, the wall

10
15

of said plenum chamber at the discharge end of the traveling grate separating the plenum chamber from an ash pit and terminating at its upper edge in a substantially horizontal surface; and a reciprocal scraper associated with the discharge end of the traveling grate and comprising an ash and refuse-receiving portion resting on the discharge end of the grate fuel-supporting surface for movement of ash thereonto and thereover, and an ash and refuse-discharging portion extending downwardly from the first-mentioned portion and resting on the horizontal surface of said plenum chamber end wall upper edge and having sliding movement on said surface during reciprocation of the scraper.

DONALD J. MOSSHART.
